MEREDITH LEITCH AND BERT ROBERT WRIGHT, OF POUGHKEEPSIE, NEW YORK,
ASSIGNORS TO THE DE LAVAL SEPARATOR COMPANY, OF NEW YORK, N. Y., A
CORPORATION OF NEW JERSEY.

FROTH-REDUCING DISCHARGE APPARATUS AND PROCESS.

1,256,810.

Specification of Letters Patent. Patented Feb. 19, 1918.

Application filed October 29, 1915. Serial No. 58,555.

To all whom it may concern:

Be it known that we, MEREDITH LEITCH and BERT R. WRIGHT, both citizens of the United States, and residing at Poughkeepsie, county of Dutchess, State of New York, have invented certain new and useful Improvements in Froth-Reducing Discharge Apparatus and Process; and we do hereby declare the following to be a full, clear, and exact description of the invention, such as will enable others skilled in the art to which it appertains to make and use the same.

This invention relates to centrifugal apparatus provided with froth reducing discharge passages and orifices, and to a process of reducing froth formation in such apparatus.

In many centrifugal devices, as, for instance, milk clarifiers, emulsifiers and homogenizers, and cream separators, which are operated at high speed, the treated liquid leaves the rotary element of the machine with such velocity that it entrains considerable air and causes a large amount of froth in the discharge liquid. In many cases, this froth is found to be very objectionable.

With the common arrangements of centrifugal apparatus, the liquid comes from the interior of the bowl and is discharged outwardly in approximately a radial direction, leaving the discharge orifice with a velocity equal to the peripheral velocity of the orifice. From such orifices the stream is discharged in the form of a broad, thin sheet, presenting a maximum area to the air and thus further increasing the production of froth, inasmuch as this thin sheet, traveling at a high velocity, tends to be broken up into a spray.

It is an object of the present invention to overcome such disadvantages and to reduce the formation of froth in such centrifugal apparatus. This is effected, first, by reducing the speed of the liquid discharged from the apparatus, and, second, by so controlling the discharge that it shall be in the form of relatively thick, solid streams having a minimum periphery, and consequently a minimum tendency to entrain air.

The reduction in speed of the liquid is accomplished by making the discharge passages from the apparatus of a trailing form so that the liquid, in passing from the interior of the apparatus outward, is propelled in a rearward direction with respect to that of rotation and discharged as nearly as possible in a direction which is tangential to the periphery at the point of discharge, and in a direction opposite to the direction of rotation of the apparatus. Instead of leaving the apparatus in a radial direction and with a velocity equal to the peripheral velocity of the discharge orifice, the liquid has a much lower radial and peripheral velocity.

The formation of streams of a minimum periphery is accomplished by making the discharge passages of such a form that these passages terminate in discharge orifices of a generally round or square cross-section. In centrifugal apparatus in which the liquid escapes over a regulating weir of the bowl in broad, thin sheets, discharge passages are constructed and arranged to catch and concentrate this sheet into thick, solid streams of the nature indicated.

Each of these arrangements results in a decrease in the froth formed. The advantages of these arrangements, however, are particularly effective in accomplishing a material reduction in the quantity of froth produced, when they are used together in the same apparatus.

The nature of the invention will more fully appear from the following detailed description of certain embodiments thereof, but it is intended and understood that the invention will be illustrative by, but is not limited to, the specific embodiments thereof thus illustrated and described.

In the accompanying drawings, Figures 1 and 2 show a cream separator embodying the invention as applied to the skimmed milk discharge, Fig. 2 being a central section, and Fig. 1 a section on the line 1-1 of Fig. 2.

Fig. 3 shows, partly in section and partly in elevation, a milk clarifier embodying the invention.

Fig. 4 is an outside view of the top of the milk clarifier of Fig. 3.

Fig. 5 shows the clamping nut of Fig. 3 removed from the milk clarifier.

Fig. 6 is a bottom view of this nut.

Fig. 7 shows a modification of the invention, and

Fig. 8 shows a further modification of the invention.

10 Referring first to Fig. 1 and Fig. 2, the cream separator illustrated is made up of the bottom 1 suitably mounted upon the propelling shaft 2, and having mounted thereon the top of the separator bowl 3. Centrally arranged within the bowl is the inlet chamber 4 having at its lower end outwardly opening passages 5 leading to the separating elements or disks 7, suitably spaced apart, the top disk being provided 15 with upwardly extending wings 8 for spacing the same from the top of the bowl. The top clamping nut is indicated at 6. Within the separator bowl is a cream disk 9, inside of which the cream passes up and then out 20 through the opening 10. The construction of the cream separator thus far described is a common construction, and is intended to illustrate a suitable cream separator structure with which the novel apparatus of the 25 present invention can be combined.

The top of the separator bowl is provided with upwardly extending passages 11 for the skimmed milk which rises outside of the cream disk 9. From these openings 11 the 30 skimmed milk overflows into the discharge passages or channels 12, the bottom edges of the openings 11 forming weirs, similar to the overflow weir of a dam. During this time the liquid is traveling at the same rate as, or 35 a little faster than, the bowl.

With previously used constructions the liquid after flowing over the top edges of the 40 passages 11, passes freely over the flat surface in a generally radial direction with a speed which increases until the liquid is finally discharged from the apparatus with a peripheral speed substantially equal to that of the discharge orifice. In the construction of Figs. 1 and 2, however, the channel or 45 passage 12 extends both outwardly and rearwardly with respect to the direction of rotation of the bowl so that the liquid in passing outward must pass rearwardly, relative to the bowl, and escape with a much reduced 50 speed.

It will be seen that the discharge passage 55 12 is of a convergent nature and concentrates the escaping liquid from a thin sheet to a stream of approximately square cross-section. By thus propelling the milk rearwardly, and discharging it in a general tangential direction, it will be seen that the velocity of the discharged stream is much less,

both radially and peripherally, than that of the periphery of the bowl from which it is 60 discharged.

By thus materially reducing the velocity of the stream, and by concentrating this stream into a thick and solid stream, as distinguished from a thin broad film, there is 70 less breaking up into a spray and much less froth formation than with constriction herefore used.

In Fig. 3 is shown a milk clarifier of the kind described in the Wright Patent No. 75 1,122,457 granted December 29, 1914. This milk clarifier is made up of the bowl member 22 mounted upon the shaft 2, and having an upper member 13 suitably secured thereto and provided with a restricted upper end. 80 Within the clarifier is the central supply member 14 from which the milk is discharged outwardly at the bottom of the clarifier through passages 15. The clarifying takes place in the outer portion of the 85 bowl from which the milk passes back between the disks 17 to the top of the bowl around the central chamber 14. A top clamping nut 16 is provided at the top of the clarifier for holding the central chamber 14 90 in proper position.

Between the neck of the clarifier bowl and the clamping nut 16 are provided discharge passages for the escape of the milk which has been clarified. In the embodiment of 95 the invention illustrated in Figs. 3, 4, 5 and 6, the nut 16 has discharge channels 20 therein on its under side, these channels extending rearwardly with respect to the direction of rotation of the bowl. In their preferred 100 form, these channels gradually change from a broad flat form at their entrance to either an approximately square or circular form at their discharge ends, so that a wide inlet is provided for the milk film which is concentrated into a thick solid stream during its 105 passage to the discharge orifices. As clearly shown in Fig. 6, these channels or passages are of a convergent nature and are so restricted and arranged as to discharge the 110 liquid therefrom in a general tangential direction, opposite to that of rotation.

In the modification of Fig. 7, the discharge channels or passages 28 are arranged in the top of the bowl instead of in the bottom of the nut 16, these passages being of a similar convergent nature, and rearwardly arranged.

In the modification of Fig. 8, channels are provided in the under side of the nut and 120 the top of the bowl, these channels being so constructed and arranged that they can be made to register with each other to form passages of a substantially rounded form at their discharge ends, although it will be understood that these passages will operate in 125

a similar manner without registration with each other.

With the arrangement of Figs. 3 to 8, the clamping nut, when removed, exposes the discharge passages so that they can be readily inspected and cleaned, and thus kept in proper sanitary condition.

The liquid, after clarification in the body of the bowl, as more fully described in Patent No. 1,122,457, rises up in a thin, annular stream inside the neck of the top 13 of the bowl and enters the channels or passages 20 and is propelled outwardly and rearwardly through them, being discharged therefrom in the form of thick, solid streams. Because of the shape and arrangement of these passages 20, the streams are gradually concentrated from a thin, flat cross-section to a more nearly round or square cross-section, and their direction is changed from radial to approximately tangential in a rearward direction, so that the absolute speed of the discharged liquid is much less than the speed of the discharge orifice.

It will be seen that in both the cream separator of Figs. 1 and 2, and in the milk clarifier of Figs. 3 to 8, the liquid is propelled from within the apparatus through an outwardly and rearwardly extending discharge passage with a reduced velocity, and in the form of relatively thick, solid streams. It will further be seen that these streams are advantageously of a convergent nature so that the milk or other liquid is concentrated from its usually broad, thin stream into a stream of a thick, solid nature and of a relatively small periphery with respect to its cross-section.

What we claim is:

1. The process of reducing froth formation in the discharge of the liquid from high speed centrifugal apparatus having an overflow discharge, which consists in propelling the liquid in an outwardly and rearwardly extending direction from the overflow point of the apparatus, and simultaneously reshaping the usual thin flat stream to a relatively thicker stream without reducing the cross sectional area, wherefore the velocity of the discharge stream and its exposed surface are both reduced.

2. The process of reducing froth formation in the discharge of liquid from high speed centrifugal apparatus, which consists in causing the liquid to follow an outwardly and rearwardly extending path as discharged from the apparatus, and simultaneously shaping the stream to reduce the perimeter without decreasing the cross sectional area and discharging the same with reduced velocity and in relatively thicker solid streams in a general tangential direction; substantially as described.

3. The process of reducing froth formation in the discharge of liquid from high speed centrifugal apparatus which comprises propelling the liquid in the form of thin sheets to the discharge passages, thence in outwardly extending converging discharge streams and finally discharging the liquid in relatively thicker independent streams; substantially as described.

4. The process of reducing froth formation in the discharge of liquid from high speed centrifugal apparatus which comprises propelling the liquid in the form of thin sheets to the discharge passages, thence in outwardly and rearwardly extending converging discharge streams, and finally discharging the liquid with reduced velocity in relatively thicker independent streams in a general tangential direction; substantially as described.

5. A liquid centrifugal apparatus provided with a plurality of relatively long discharge weirs, and, leading from each weir, an outwardly extending discharge passage converging in one direction proportioned and arranged to discharge the liquid therefrom in solid streams thicker than at the weir and without increase in nozzle velocity; substantially described.

6. A liquid centrifugal apparatus provided with a plurality of relatively long discharge weirs, and, leading from each weir, an outwardly and rearwardly extending discharge passage, said passages being of an outwardly converging nature and arranged to discharge the liquid therefrom in solid streams without increase in nozzle velocity and in a general tangential direction; substantially as described.

7. A liquid centrifugal apparatus provided with a bowl having an upwardly extending neck, and a clamping nut, outwardly and rearwardly extending discharge passages being provided between the bowl neck and nut so proportioned and arranged as to discharge the liquid in separate streams and in a general tangential direction without increase in nozzle velocity; substantially as described.

8. A liquid centrifugal apparatus provided with a bowl having an upwardly extending neck, and a clamping nut, outwardly and rearwardly extending discharge passages of a convergent nature being provided between the bowl neck and nut arranged to discharge the liquid in separate streams and with reduced velocity in a general tangential direction; substantially as described.

9. A liquid centrifugal apparatus, provided with a discharge-controlling weir over which the liquid passes in thin ribbon-like stream, and provided further with a rearwardly-curved discharge passage leading

from said weir and so proportioned and arranged as to gather said ribbon-like stream into a relatively thick stream of diminished periphery; substantially as described.

10. A liquid centrifugal apparatus, provided with a discharge controlling weir over which the liquid passes in thin ribbon-like stream, and provided further with a converging channel leading from said weir

and terminating in a discharge aperture of relatively small periphery from which the liquid issues in a thick stream of correspondingly diminished periphery; substantially as described.

15 In testimony whereof we affix our signatures.

MEREDITH LEITCH
